UNITED STATES PATENT OFFICE

CHARLES DENNISTON BURNET, BARNES NEVILLE WALLIS, AND JOHN EDWIN TEMPLE, WESTMINSTER, LONDON, ENGLAND, ASSIGNEES TO AIRSHIP GUARANTEE COMPANY, LIMITED, OF WESTMINSTER, ENGLAND, A BRITISH COMPANY

RIGID AIRSHIP

Application filed August 20, 1927, Serial No. 214,328, and in Great Britain September 17, 1926.

This invention relates to rigid airships. In rigid airships the main structure of the hull usually consists of longitudinal girders and transverse frame members, the latter being usually in the form of polygonal rings. 5 Each transverse frame is usually also provided with a system of internal bracing wires (hereinafter termed the bulkhead wiring) which extends transversely across each transverse frame and interconnects the corners of 10 the polygon.

In order to secure stability in the frame structure, both under normal and abnormal conditions, and especially in cases where the 15 frame or ring members are constituted by relatively shallow girders, for example by girders the depth of which is of the order of approximately 2% or under of the diameter of the frame, it is essential that the frame 20 shall be provided with a system of bulkhead wiring which will not only be adequate to restrain deflection of the ring members under the load imposed upon them during normal flight when both the gas bags located on 25 contiguous sides of the bulkhead wiring are fully inflated, but which will also be of such a strength or character that, if one of the gas bags becomes deflated, the tension set up in the bulkhead wiring, due to the end pressure 30 of the contiguous inflated gas bag or bags as it or they protrude or tend to protrude laterally into the space formerly occupied by the deflated bags, will not throw too great a compression into the transverse 35 frame members.

It has heretofore been impossible to comply with both these conditions in a satisfactory manner, for, if the bracing wires are put in either hand taut or with initial tension 40 in order to brace a light and shallow transverse frame under normal conditions, then, under abnormal conditions, and when a gas bag is deflated the end pressure of the contiguous inflated bag or bags on the bulkhead wiring sets up a high degree of compression in the frame members which might cause failure or deformation in a light or narrow frame and therefore in certain cases might impose secondary forces and/or bending 45 moments in the longitudinal girders. On

the other hand if the frames are made sufficiently strong or sufficiently deep to resist deformation or any stresses set up in the deflated bag condition the additional weight of such frames, to provide for a circumstance 55 which is actually of abnormal or unlikely occurrence, is objectionable to a high degree in a structure where the maximum degree of lightness consistent with strength is the desideratum.

According to one feature of the present invention the wires constituting the bulkhead wiring of each transverse frame are so arranged that they radiate outwards in all directions and at a suitable distance apart from a point located at or about the axis of the ship, but the outer ends of the wires or certain of the wires, are connected to catenaries the ends of which are in turn attached to the transverse frame members at the point where 60 they are intersected by the longitudinal girders.

The adoption of this arrangement ensures an even distribution of the lateral loading in the bulkhead wiring to all members of the transverse frame, especially in cases where, as described in co-pending application Serial No. 214,036, filed August 19, 1927 a connection is made, from the point where each catenary joins the frame members, to the circumferential mesh wiring surrounding each gas bag. This system is employed in combination with an axial restraint, that is to say the centres of the radially arranged bulkhead wires are interconnected by a stranded 75 wire or cable running axially of the ship, or connected to a centrally arranged and rigid girdle running axially of the ship as herein-after more particularly described.

In the foregoing arrangement all the radially arranged wires in each panel (i. e. the wires connected to the same catenary) are hand taut (i. e. have an initial tension of approximately 50 to 100 lbs.) in order to brace the frame under normal conditions and to transmit to the framework in a more satisfactory manner than heretofore the lateral loading of the bulkhead wiring under abnormal or deflated bag conditions. According 85 to, however, to a further feature of the 90

present invention and to a preferred arrangement only the radially arranged end wires of each panel have initial tension or are hand taut and, disposed between the taut wires of each panel, is a catenary to which a number of radially arranged and initially slack wires are attached, each catenary extending between a polygonal side of the transverse frame and having each of its ends attached to the frame at the points where it is intersected by a longitudinal girder. The taut wires are attached to the frame members at the same point and/or contiguous to the slack wires.

According to another feature of the present invention an axial restraint is provided at or about the centre of the bulkhead wiring. The axial restraint may be constituted by a stranded wire cable running axially of the ship through the gas bags and having its ends secured to the framework at the nose and tail of the ship. The use of a cable, however, is open to certain disadvantages in that it extends under the influence of the lateral loading on the bulkhead wiring, so that it is difficult to determine whether or not the centre of the radial wiring is restrained in the plane of the transverse frame. Furthermore, the cable has to be located in position when the gas bags are partially inflated, and, apart from the fact that leakage of the lifting gas occurs, or is liable to occur, at the openings through which the cable enters and leaves the gas bags, the attachment of the cable in position is very troublesome. Instead of a cable, therefore, it is preferred to provide an axial restraint constituted by a rigid girder which is preferably constructed in sections and which has its ends restrained at the nose or tail of the ship in such a manner as to transmit the loads which may occur in the axial girder into the longitudinal girders of the hull. In order to accommodate the rigid girder a central opening or core is provided through the axis of each gas bag, the openings being preferably lined with heavier material than that of which the bag itself is composed. The axial girder may be of space frame construction and of triangular cross section and be built up from sections which are joined together in a detachable manner at points in or about the plane of the bulkhead wiring.

In order that the said invention may be clearly understood and readily carried into effect the same will now be described more fully with reference to the accompanying drawing, in which:—

Figure 1 is a cross-section of an airship fitted with a system of tight and slack bulkhead wiring constructed according to the present invention, as also with an axial restraint constituted by a built-up space frame girder, part only of the slack wiring as also the covering network being shown.

Figure 2 is a typical section showing the bulge of the gas bag between the taut radial wires when the adjoining gas bag is in deflated condition.

Figure 3 is a view on an enlarged scale showing a panel constituted by a catenary, a pair of tight wires and a number of slack wires.

Figure 4 is a sectional view showing diagrammatically on an enlarged scale the relative bulge at half radius of the tight and slack wires of a panel when in deflated bag condition.

Figure 5 is a detail view showing one method which may be adopted for connecting the ends of the catenaries, as also the tight wire to the framework of the airship.

Figure 6 is a detail view showing one method that may be adopted for connecting the inner ends of the tight and slack wires to a hub located at the axis of the ship.

Figure 7 is a corresponding view to Figure 6, showing in greater detail the construction of the said hub.

Figure 8 is a diagrammatic view of an airship constructed according to the present invention showing the axial girder which extends lengthwise of the ship, and

Figure 9 is a detail view showing on a larger scale the hub at the axis of the ship to which the ends of the taut and slack radial wires are attached, as also a portion of a spider which is mounted on the said hub and by means of which the axial girder is secured in position.

A, A are the transverse frame members and B, B the longitudinal girders, C is the axial girder which restrains the gas bags in the plane of the transverse frame A, D, D are the hubs at the axis of the ship and E, E are the spiders for coupling together the parts of the girder C constituting the axial restraint. F, F are the tight wires of the bulkhead wiring and G, G are the slack wires. H, H are the slack catenary wires for attaching the slack wires of the bulkhead wiring to the transverse frame members. I is a cord netting covering the corner gaps between the catenaries of the circumferential mesh wiring which surrounds the gas bags and the bulkhead wiring catenaries. J is a cord netting interlaced between the taut and slack wires, F, F and G, G to prevent undue bulging of the gas bag through the said wires. K (Figure 2) is an inflated gas bag and K¹ is a deflated gas bag, the gas bags throughout the ship being provided with an axial trunk K² to accommodate the axial girder C. In the example shown at Figure 1 the airship is provided with a corridor L extending lengthwise of the ship and the slack wires G in the panel above the same are of shorter length than those of other panels.

A suitable mode of attaching the catenaries

H, H and the taut wires F, F consists in bringing the end of a taut wire F and each end of a pair of contiguous catenaries H, H within a socket piece H¹ and locating the latter within, or attaching it to the transverse frame A, turnbuckles H², H² being provided towards the ends of the catenary wires and the taut wires to effect the necessary adjustments. By means of this preferred arrangement there is provided a primary system of radially arranged and hand taut wires F, F which is adequate to brace or restrain deflections of the relatively light transverse frames A, A under normal conditions but not adequate to cope with abnormal or deflated gas bag conditions, and a secondary system of slack radial wires G, G disposed between the taut wires F, F which normally hang more or less loosely and only come into action during abnormal or deflated gas bag conditions, and which, by virtue of their initial slackness, are free to curve or bulge outwardly beyond the plane of the tight wires under deflated bag conditions, so that, for an equal lateral loading they suffer less tension than the tight wires.

In the event of a bag becoming deflated both the tight and the slack wires are bulged outwardly as shown at Figures 2 and 4 by the end pressure of the contiguous inflated gas bag K beyond the plane of the transverse frame A, but the slack wires G, G as a whole bulge beyond the tight wires while the gas bag itself protrudes through and beyond the spaces between all the radial wires, thus causing the protruding inflated gas bag to assume a fluted or "cantaloupe-like" configuration. As the ends of the catenary H to which the slack wires G, G are attached are not anchored to the taut wires F, F but independently attached to the transverse frame A their radial tension is separately transferred to the frame at each corner of the polygon, and not to or through the taut bracing wires F, F. Owing to this arrangement the total radial loading in the bulkhead wires in deflated gas bag conditions which is transferred as a compressional force to the transverse frame members from the connections at each polygonal angle thereof is less than would be the case if all the wires of the bulkhead wiring were initially taut in normal bag conditions, as has invariably been the case in all previous proposals to use a relatively narrow or shallow frame. The cord net J is preferably provided to restrain undue bulging of the gas bag in the spaces between the system of radially arranged wires and this cord network covers both the taut and the slack wires. If desired, and in cases where the point of connection of the taut wires and the ends of the catenaries does not pass through the centroid of either or both the transverse frame members and the intersecting longitudinal girders a connection may be made from the said

point of attachment to the circumferential mesh wiring by means of a strop or otherwise as described in our co-pending application Serial No. 214,036, filed August 19, 1927. The longitudinal girders and the transverse frame members may also be so arranged that they intersect one another in such a manner that their centroids are coincident and the lift and shear wires may be attached at or approximately at the said coincident centroids, a suitable method of obtaining this result being described in our co-pending patent application Serial No. 214,028, filed August 19, 1927.

In view of the fact that the resultant normal pressure on the bulkhead wiring is greater at the top than at the bottom of the bag, it is highly desirable, in order to prevent the occurrence of unequal stresses or bending moments in the framework, that the inward radial loading due to endwise pressure on the bulkhead wiring in deflated bag conditions should be equal at each corner of the polygon. To this end the degree of slackness initially imparted to the slack wires of each successive panel can be made progressively greater from a minimum at the bottom of the airship to a maximum at the top thereof.

This result can readily be obtained by locating the catenaries H, H in place and thereafter, by means of the aforesaid turnbuckles H², H² located between the ends of the catenaries and their connections to the transverse frame, slackening out or otherwise adjusting them to the predetermined extent. At their inner ends the taut and the slack wires are attached to the hub D as shown more clearly at Figures 6 and 9 and if desired turnbuckles may also be provided for adjusting the ends of the taut wires.

A suitable method of detachably connecting the various sections of the girder to one another in cases where the girder is of triangular space frame construction, constituted, as in the example illustrated, by three tubular members connected together by bracing members, is shown more clearly at Figure 9 where a member E (which is termed a spider) is provided having three radial arms e (one complete arm only being shown) each arm being provided at its outer extremity with a socket e¹ which accommodates a connecting piece having screw-threaded ends to which the end members of the triangular space frame girder on contiguous sides thereof are attached by removable coupling rings. Projecting laterally of the spider and attached thereto at the centre thereof in any suitable manner may be a stub shaft e² on which a pair of plates constituting part of the hub D are mounted, the plates being spaced apart by angularly displaceable fittings to which the ends of the taut and slack wires of the bulkhead wiring are se-

cured. The said stub-shaft e^2 may also be provided with bollard pieces d to support the ends of cables d' from which the fuel tanks, ballast, etc., may be suspended.

5. In locating the axial girder C in position a gas bag is suitably arranged around each section of the girder and bound in place. Thereafter the sections are hoisted into place and coupled together by the coupling pieces carried on the spiders E, the binding for the gas bags is then removed and they are allowed to hang from the axial girder C. The provision of an axial girder has the advantage that each gas bag is supported at half its height during the filling operation instead of lying on the bottom of the airship, and, especially in the larger sizes of airships where the gas bags are of great capacity, this arrangement is advantageous in that it allows the supported bags to fill out in a position where damage to the bag is unlikely to occur. Moreover, in deflated bag condition the bag is supported on the girder section at the axis of the ship where it may be possible to effect a repair without removing both the girder section and the damaged bag from the ship. As, in deflated gas bag condition, the girder section in the bay containing the damaged bag will be in compression and the remaining girder sections of each side thereof in tension, means may be provided for retracting the portions of the girder on each side of the section containing the damaged gas bag to relieve the said section from compression and enable it to be removed.

40. The provision of an axial restraint constituted by a rigid sectional girder fixes definitely the centres of the bulkhead wiring in the plane of each transverse frame. If desired, the space frame girder constituting the axial restraint may be used for leading controls, etc., along the ship, or enlarged so as to form an access passage extending from the bow to the stern of the ship.

45. What we claim and desire to secure by Letters Patent of the United States is:—

1. A rigid airship in which the wires constituting the bulkhead wiring radiate outwards in all directions, and at a suitable distance apart, from a point located at or about the axis of the ship, the outer ends of the wires, or certain of them, being connected to catenaries, the ends of said catenaries being attached to the framework of the airship at the points where the transverse frame members are intersected by the longitudinal girders.

50. 2. A rigid airship in which the bulkhead wiring comprises a number of initially taut wires and a number of initially slack wires all radiating from a common point in proximity to the axis of the ship.

55. 3. A rigid airship in which the bulkhead wiring comprises a number of initially taut wires and a number of initially slack wires

all radiating from a common point in proximity to the axis of the ship and the inner ends of the slack wires are attached to a point at or about the axis of the ship and the outer ends are connected to catenaries, the taut wires being also radially arranged with their inner ends attached to a point at or about the axis of the ship; the ends of said catenaries as also the outer ends of the taut wires being connected to the framework of the airship at the points where the transverse frame members are intersected by the longitudinal girders.

4. A rigid airship as claimed in claim 3, in which the contiguous ends of a pair of catenaries as also the end of a taut wire are brought within a socket piece which is located within or attached to the transverse frame.

5. A rigid airship as claimed in claim 3, in which turnbuckles or other tautening devices are provided to enable any necessary adjustment of the taut wires, the slack wires and the catenaries to be effected.

6. A rigid airship as claimed in claim 3, in which connections are made from the point of attachment of the catenaries to the circumferential mesh wiring.

7. A rigid airship as claimed in claim 3, in which the intersecting longitudinal girders and the transverse frame members are so arranged that their centroids are coincident.

8. A rigid airship as claimed in claim 3 in which the degree of slackness initially imparted to the slack wires of each successive panel is made progressively greater from a minimum at the bottom of the airship to a maximum at the top thereof.

9. A rigid airship as claimed in claim 3 in which an axial restraint is provided at or about the centre of the bulkhead wiring.

10. A rigid airship as claimed in claim 3, in which an axial restraint constituted by a rigid girder is provided in proximity to the center of the bulkhead wiring, the taut and slack wires being attached thereto.

11. A rigid airship, comprising in combination longitudinal and transverse rigid members, provided with an axial restraint constituted by a rigid girder constructed in removable sections, bulkhead wiring attached to said transverse members and to said girder, and means whereby the portions of said girder on opposite sides of any one of said removable sections (other than the end sections) may be retracted from said section to permit of its removal.
